UNITED STATES PATENT OFFICE.

HERBERT TOWNSEND, OF PHILADELPHIA, PENNSYLVANIA.

HEATER.

Application filed October 22, 1920. Serial No. 418,821.

To all whom it may concern:

Be it known that I, HERBERT TOWNSEND, a subject of the King of Great Britain and Ireland, residing at Philadelphia, in the county of Philadelphia and State of Pennsylvania, have invented new and useful Improvements in Heaters, of which the following is a specification.

My invention relates to new and useful 10 improvements in heaters, and has for its object to construct a device of this character in such manner as to cause a circuitous circulation of air therethrough so that air passing therethrough will be raised in temperature 15 and cause the walls to be heated so that air passing through only parts of the heater will be raised in temperature and then distributed from the top of said heater.

Another object of the invention is to provide a heater with passageways certain ones of which are formed of pipes, said pipes being spaced apart to provide air passageways therebetween.

A further object of the invention is to construct a heater having passageways as above described and including a hood and the covering for catching the products of combustion from the burner from which said products of combustion are conveyed to a chimney by means of a pipe and having a pipe leading from the top of the heater proper for conveying heated fresh air to a room or chamber to be heated.

A still further object of the invention is to provide a double walled partition forming the upper passageways so as to produce a water jacket whereby a circulation of water may be raised in temperature and distributed about a building for heating the rooms 40 thereof.

With these ends in view, this invention consists in the details of construction and combination of elements hereinafter set forth and then specifically designated by the 45 claims.

In order that those skilled in the art to which this invention appertains, may understand how to make and use the same, I will describe its construction in detail, referring 50 by numerals to the accompanying drawings forming a part of this application, in which:—

Fig. 1, is a side elevation of a heater embodying my improvements, a portion thereof being broken away and shown in section to clearly illustrate the construction.

Fig. 2, is an inner plan view of the top or cap of the heater.

Fig. 3 is a side elevation or edge view thereof having a portion broken away and shown in section.

Fig. 4, is a section at the line 4—4 of Fig. 1.

Fig. 5, is a view similar to Fig. 1 of a modification showing the hood applied thereto for catching the products of combustion and illustrating the pipe passing through said hood from the top of the heater for distributing heated fresh air.

Fig. 6, is a plan view partly broken away and shown in section illustrating the heater constructed for use as a hot water heater.

Fig. 7, is a side elevation thereof partly broken away and shown in section to illustrate the construction.

In carrying out my invention as embodied in Figs. 1 to 4 inclusive, 2 represents the base of the heater comprising a bottom 3 supported on suitable legs or feet 4 and having a side wall 5 forming a burner chamber 6, the upper portion of which is partially closed by the burner chamber top 7 having a central opening 8 therethrough. Extending from the burner chamber and the top 7 surrounding the opening 8 is the stack 9 open at both ends.

From the burner chamber top 7 projects an extension wall 10 in line with the side wall 7 and this extension wall supports or carries the trunk supporting head 11 having a plurality of openings 12 therein, each opening being surrounded by an upwardly projecting flange 13. The head 11 also has a central opening 14 of greater size or diameter than the stack 9 so as to be spaced from the latter and from this head 11 extends an upwardly projecting heating drum 15 surrounding the opening 14, while its upper end projects above the stack 9 and is closed by the drum top 16, thereby forming with the stack 9 a passageway for air passing through the stack.

On each of the flanges 13 so as to surround the same is mounted a pipe 17 normally open at each end and these pipes are located about the heating drum and spaced therefrom and from each other so as to form air passageways 18 therebetween leading to the heating drum.

The upper ends of these pipes are held in their positions by a ring 19 which may be a separate piece and secured to the pipes.

by some suitable fastening means such as rivets, or said ring may be carried by or formed as an integral part of the top or covering 20 having a central portion or plate 5 21 provided with perforations 22 and having integral radiating arms 23 to cover the upper ends of the pipes 17 and these arms are provided with perforations 24 for the outlet of the heated air which is also the 10 purpose of the perforations 22.

In the burner chamber 6 is located a burner 25, the one here shown representing an ordinary gas burner but this burner may be of any desirable construction suitably 15 adapted for using oil or other fuel for producing the required heat.

In practice the walls of the heater will be heated by the flame from the burner 25 so that air passing into the burner chamber 6 through the opening 26 in the bottom wall 3 of the base will pass over the flame of the burner and will be raised in temperature as it comes in contact with the different walls of the heater during its passage 20 through the stack 9 then over said stack and downward between the walls thereof and the walls of the heating drum then beneath the head 11 and upward through the different pipes 17 from which it will pass out 25 through the perforations 24, and at the same time fresh air will flow through the passageways 18 between the different adjacent pipes 17 until it contacts with the heating drum where the temperature of the 30 air will be raised and caused to flow upward and because of the ring 19 said heated air will pass toward the center of the heater and then out through the perforations 22 in the central portion of the 40 top 20.

Because of the construction here illustrated an exceedingly large heating area is provided and because of the circuitous passageways formed it has been found that the air 45 is sufficiently agitated or broken up to cause it to absorb a great amount of heat which is of great advantage in devices of this character.

In Fig. 5, I have shown a modified form 50 of my invention in which a hood 30 forms the upper outer shell of the heater and surrounds the trunks or conduits but spaced therefrom and this hood is provided with feet or projections 31 at the bottom thereof 55 so as to rest upon the head 11 thereby leaving open spaces for the passage of air into said hood and then between the pipes 17 in its movement toward the heating drum. This hood is closed at the top except for a 60 hole 32 for a purpose hereinafter described and leading from said hood, near the upper end thereof, is a smoke pipe or flue 33 for conveying the products of combustion, which pass upward through the trunks, to 65 a chimney or other suitable outlet.

A ceiling 27 is provided to take the place of the top or cover 20 and is disposed across the interior of the hood above the pipes 17 having openings 50 for the pipes 17 and a central opening 28 from which leads a pipe 70 29 for distributing the heated air which passes between the pipes 17 and over the heating drum, said pipe 29 projecting through the hole 32 in the top of the hood. In all other respects the construction is 75 identical to that hereinbefore described.

In Figs. 6 and 7, 34 represents the outer wall or shell of the heater having a burner chamber top 35 disposed across the interior thereof to form the burner chamber 36 in 80 which the burner 37 is located. The burner chamber top is provided with an opening 38 about which is disposed a stack 39 projecting upwardly from the wall 35.

Surrounding the stack 39 and spaced 85 therefrom is a water jacket 40 which acts similar to the heating drum 15 so as to produce with the stack and the shell a circuitous air passageway and said shell preferably has a top wall 41 with a hole 42 therethrough for the exit of the air. The water jacket has a water inlet pipe 43 leading thereto adjacent its lower end and a water outlet pipe 44 at its upper end so that water entering the jacket will circulate 90 around the same and be heated by the circulation of warm air thereto.

Of course I do not wish to be limited to the exact details of construction as herein shown as these may be varied within the 100 limits of the appended claims without departing from the spirit of my invention.

Having thus fully described my invention, what I claim as new and useful is:

1. A heater comprising in combination, a 105 base having a burner chamber therein, a stack supported by the base and communicating with the burner chamber, a head also supported by the base, said head having a central opening of greater diameter than 110 the stack through which the latter passes and a plurality of surrounding openings, said head with the top of the burner chamber forming a passageway for air from the central opening to the other openings, a heating drum supported by the head about the central opening, said drum being closed at its upper end and open at its lower end and partially enclosing the stack with its walls spaced therefrom, pipes also supported by 120 the head and surrounding the other openings therein, said pipes being so spaced as to permit air to circulate therebetween for passage to the heating drum and a perforated top supported by the pipes for covering their upper ends and the space bounded by said pipes.

2. A heater comprising in combination, a 125 base having a burner chamber therein, a stack supported by the base and communi- 130

- cating with the burner chamber, a head also supported by the base, said head having a central opening of greater diameter than the stack through which the latter passes 5 and a plurality of surrounding openings, said head with the top of the burner chamber forming a passageway for air from the central opening to the other openings, a heating drum supported by the head about 10 the central opening, said drum being closed at its upper end and open at its lower end and partially enclosing the stack with its walls spaced therefrom, pipes also supported by the head and surrounding the other 15 openings therein, said pipes being so spaced as to permit air to circulate therebetween for passage to the heating drum, a ring connected with the inner walls of all of said pipes at their upper ends, a perforated top 20 plate covering the space bounded by said pipes and perforated arms radiating from the top plate and covering the upper ends of said pipes.
3. A heater comprising in combination, a base having a burner chamber therein, a stack supported by the base and communicating with the burner chamber, a head also supported by the base, said head having a central opening of greater diameter 25 than the stack through which the latter passes and a plurality of surrounding openings, said head with the top of the burner chamber forming a passageway for air from the central opening to the other openings, a heating drum supported by the head about 30 the central opening, said drum being closed at its upper end and open at its lower end and partially enclosing the stack with its walls spaced therefrom, pipes also supported 35 by the head and surrounding the other openings therein, said pipes being so spaced as to permit air to circulate therebetween 40
- for passage to the heating drum, a top, a pipe leading from said top and communicating with the space above the heating drum, a hood surrounding the pipes with its top wall spaced from the upper end of said pipes and its side walls spaced from the sides of said pipes, said side walls terminating short of the base to leave a passageway to the interior of the hood, feet on 45 said hood for supporting it on the base and a flue leading from the upper part of said hood.
4. A heater comprising a base having a burner chamber therein and including a centrally apertured top wall, an extension wall projecting from the base, a head supported by the extension wall and parallel with the said top wall to form an air passageway, said head having a central opening and a plurality of other openings surrounding the central opening, a stack supported by the base and surrounding the aperture in its top wall, said stack projecting 50 through the central opening in the head, a heating drum open at the bottom and closed at the top surrounding the upper part of the stack and spaced therefrom, said stack being supported by the head and communicating with the central opening in said head, pipes communicating with the other openings in said head, whereby air passing through the stack to the heating drum will 55 be conveyed to said pipes through the passageway between the head and the top wall of the base and perforated means overlying the upper ends of said pipes and the space bounded thereby, the spaces between adjacent pipes being uncovered. 60
- In testimony whereof, I have hereunto affixed my signature.

HERBERT TOWNSEND.
